J. F. & M. Battershall

Candle Mold.

No 10,331

Patented Dec. 20, 1853

UNITED STATES PATENT OFFICE.

D. E. BATTERSHALL AND M. BATTERSHALL, OF TROY, NEW YORK.

CANDLE-MOLD MACHINE.

Specification of Letters Patent No. 10,331, dated December 20, 1853.

To all whom it may concern:

Be it known that we, D. E. BATTERSHALL and M. BATTERSHALL, of Troy, in the county of Rensselaer and State of New York, have invented certain new and useful Improvements in Machines for Making Candles; and we do hereby declare that the following is a full, clear, and exact description of the same, reference being had to the annexed drawings, making a part of this specification, in which—

Figure 1 is a top view of the machine, showing the construction and arrangement of the jaws. The dotted lines show the positions of the jaws, &c., when set in readiness for springing. Fig. 2 is a front elevation, showing the construction and arrangement of parts for setting the jaws, &c. The dotted lines show the positions of the working parts when the jaws are set in readiness for springing. Fig. 3 is an end view. Fig. 4 is a longitudinal sectional view, taken at the line *w w* of Fig. 1. Fig. 5 is a transverse sectional view taken at the line *x x* of Fig. 2. Fig. 6 is a horizontal sectional view taken at the line *Y Y* of Fig. 2. Fig. 7 is a detached view of the horizontal sliding bar. Fig. 8 is a detached view of the oblique shoulder on the vertical sliding bar. Fig. 9 is a detached perspective view of the jaw containing the wick cutter and centering plate, and Fig. 10 is a detached view of the jaw with the wick holder.

The same letters refer to like parts in each of the figures.

The nature of our invention consists in the peculiar mode or manner of cutting, centering, and holding the wick tight in the molds, in readiness for use, by means of spring jaws, with cutter, centering plate and wick holder arranged on the top or face of the machine and molds, also a wick tightener arranged at the bottom of the machine.

The construction is as follows:

- 45 A A is the frame work.
- B B are the candle molds.
- C is the top or face of the machine.
- D is the bottom.
- E is a vertical bar the upper end of which is curved so as to form the handle (a). This bar slides up or down in grooves or bearings in the frame work and bottom. Upon the back of the bar is the oblique

shoulder (b) formed by cutting away part of the thickness of the bar.

55 F is an eccentric plate, secured to the frame work by the pin (c) and upon which it swings. At the upper corner of said plate is a curved slot (d). A pin (e) passes through this slot, and screws into the vertical bar. The opposite corner and side of the plate bear against and slide on the pin (f) screwed into a horizontal sliding bar G which slides in the case (g) or in suitable grooves for that purpose. This bar is constructed as seen in Figs. 6 and 7. (h) is a notch on the under side of it for the purpose of allowing the point of the catch or pawl (i), when the notch is brought over it, to catch against it and prevent the bar 60 from slipping back until desired. Each end of this bar is attached by connecting rods (j j) to each end of the crank arms (k k) of the shafts (l l), the lower ends of which rest upon the steps or bearings (m m). The 65 upper ends pass through the face or top of the machine, and have attached to them the buttons or tumblers H H which are rounded off at each end, as shown in the drawing, so as to bear against and force open the jaws 70 J and J'. 75

(n), Figs. 5 and 9, is the wick cutter, which is secured firmly in the jaw by screws, and can be removed easily when necessary to sharpen it.

80 (o) is the guide plate for centering the wicks.

(p) is a flange or wick holder on the jaw J', and when the jaws are closed fitting snugly between the cutter and guide plate 85 for the purpose of holding the ends of the wicks tight.

(q q) are guide bars upon which the jaws slide.

(r r) are flat bow springs for forcing the 90 jaws together when required to cut, center, and hold the wicks.

K K are wick spools, the wicking drawn in red lines.

L is the wick tightener, which is so made 100 as to have a section of it in the shape as seen at Fig. 5, and attached to it is a wing, which serves to stiffen the shaft as well as assists in tightening the wick. The tightener is then adjusted by means of the crank 105 handle (s), which passes through the end

of the machine, and is held in the required positions by means of notches in the spring catch (*t*). The tightener plate (*u*) is arranged directly under the tightener and is 5 for the purpose of tightening the wicks on.

(*v*) is a strip of leather packing for the cutter to cut the wicks on.

The operation of the machine is as follows: The spools having been supplied with 10 wicking the ends of which are passed through guide holes in the tightening plate, thence under the shaft of the tightener into and through the molds to the centering plate in the jaws, where they are held fast, 15 the wicks are then sufficiently tightened by turning the tightener down upon them, holding them securely between the tightener and plate by means of the handle and spring catch. The molds are now filled with tallow, 20 ice or snow having previously been placed around the molds to expedite the cooling of the candles, which being cold are now ready for drawing. The jaws are opened by pushing down the vertical bar, 25 which causes the eccentric plate by means of the connecting pin in the curved slot to bear on the pin in the horizontal sliding bar, thereby moving the bar, and with it the connecting rods, crank arms, and tumblers or buttons, which force the jaws open 30 against the springs until the different moving parts assume the respective positions as shown by the dotted lines, and held in such position by the catch or pawl slipping 35 into the notch on the under side of the horizontal bar, and prevented from returning, the superfluous tallow being removed by a scraper, the wick tightener unloosened. The 40 candles are drawn by means of nippers ordinarily used for that purpose. The jaw of the nippers has a shoulder to fit against

a notch in the handle of the vertical bar, so as to draw the bar up with it until the candles clear the molds, when the oblique shoulder on the back side of the bar strikes 45 the pawl and permits the springs to act on the jaws, which shut with sufficient force to cut the wicks from the candles drawn from the molds and center and hold the wick ends of a new set. 50

The advantages of this improvement consist in allowing the candles to be removed as soon as drawn from the molds, so that the gloss and fine finish of the candles is 55 retained, they not being exposed to the injurious effects of heat from the hot tallow, as they are in the old modes of drawing; also, in the cheapness, efficiency and rapidity with which the machine can be worked.

Having thus described our invention, 60 what we claim as new and desire to secure by Letters Patent, is:

1. The arrangement for cutting, for centering, and for holding the wicks at one and the same operation, by means of the 65 cutter, guide plate, jaws, springs, tumblers, crank arms, connecting rods, horizontal sliding bar, pawl, eccentric plate, and vertical sliding bar, the respective parts being 70 arranged, and operating substantially in the manner, and for the purposes as herein described and represented.

2. We claim the wick tightener, 75 constructed and operating, substantially in the manner, and for the purposes as herein described and shown.

D. E. BATTERSHALL.
M. BATTERSHALL.
